Primary Examiner — Philip S Hyder*Assistant Examiner* — Roselynne Cody(74) *Attorney, Agent, or Firm* — Cermak Nakajima LLP;
 Tomoko Nakajima(57) **CLAIM**

The ornamental design for a sprinkler cover plate assembly installation tool, as shown and described.

DESCRIPTION

FIG. 1 is a front elevational view of a sprinkler cover plate assembly installation tool showing my new design;
 FIG. 2 is a rear elevational view thereof;
 FIG. 3 is a right side elevational view thereof;
 FIG. 4 is a left side elevational view thereof;
 FIG. 5 is a top plan view thereof; and
 FIG. 6 is a bottom plan view thereof.
 FIG. 7 is a front, bottom and right perspective view thereof;
 and
 FIG. 8 is a rear, bottom and left perspective view thereof;
 FIG. 9 is a front elevational view thereof; and,
 FIG. 10 is a cross-sectional view thereof taken along the line 10-10 shown in FIG. 9.
